UNITED STATES PATENT OFFICE

OLE G. NELSON, OF BRIDGEPORT, CONNECTICUT, ASSIGNOR TO THE BEAD CHAIN MANUFACTURING COMPANY, OF BRIDGEPORT, CONNECTICUT, A CORPORATION OF CONNECTICUT

ATTACHING DEVICE

Application filed May 6, 1932. Serial No. 609,735.

This invention relates to attaching devices of the type adapted to prevent unauthorized removal of the element attached thereby, such as a tethered pencil.

5 The main object of the invention is to facilitate authorized replacement of the element attached, without permitting unauthorized removal.

10 Further objects are to simplify and improve the construction and operation of devices of this character, to render them inexpensive to manufacture, convenient in use, and otherwise well adapted for the purposes set forth.

15 Other objects and features of novelty will be apparent as the following description proceeds, reference being had to the accompanying drawing, in which

20 Figure 1 is a front elevation of a preferred embodiment of the present invention;

Figure 2 is an enlarged detail view of the same, parts being broken away and shown in section to illustrate the construction;

25 Figure 3 is a side elevation of the top portion of Figure 2, similarly broken away and with the key removed;

Figure 4 is a section taken along the line 4—4 of Figure 1; and

30 Figure 5 is a section taken along the line 5—5 of Figure 2.

The attaching device comprises a movable, preferably swiveled, socket for receiving the element to be attached, so that the element may not be disconnected unless the swivel is held from moving with the element, preferably by locking the swivel.

35 In the form shown, the relatively movable parts comprise a shell 10 and a socket member 11, preferably swiveled thereto. The shell 10 is tethered, preferably by a bead chain 12 secured to the shell by a bail 13. The socket member 11 receives the end of a pencil 14, shown as an example of the element which may be attached.

40 The socket member 11 has a conical internally threaded recess 15, into which the end of the pencil 14 may be screwed, when the member 11 is held against moving with the pencil. For this purpose a non-circular por-

tion is provided for the member 11, such as a groove 16, which may receive a key 17.

An aperture 18 is provided in the shell to admit the key 17 to the non-circular portion 16. A portion of the shell 10 is of reduced diameter, forming an annular shoulder 19 and a skirt portion 20. The shoulder 19 retains the member 11 swiveled in the shell, while the skirt portion 20 forms a mouth aligned with the recess 15, to guide the end of the pencil 14 into the socket.

55 The shell 10 may comprise a metal tubular wall 21 and a metal cap 22 suitably secured thereto. In the form shown, the cap 22 has a depending annular flange 23 inside the wall 21. With this arrangement, the socket member 11 has a surface of revolution 24 swiveled in the shell between the shoulder 19 and the rim of the flange 23. The upper rim of the wall 21 is preferably crimped or spun over the edge of the cap as at 25, and the ends of the bail 13 pass through apertures 26 in the wall 21, into slots 27 in the flange 23. The aperture 18 which admits the key may be a rectangular slot formed in the top of the cap 22.

60 With the device as described above, the key is inserted through the slot 18 into the groove 16. The end of the pencil 14 is then screwed into the socket 15. The key is then removed. The pencil may not be removed, as any turning thereof will merely turn the swiveled socket. The pencil may be replaced by again inserting the key to hold the socket and permit the pencil to be unscrewed.

65 The invention is not to be limited to the details disclosed, but instead the invention includes such embodiments of the broad idea as fall within the scope of the appended claims.

I claim:

70 1. An attaching device comprising relatively movable parts, one of said parts overlying the other, said overlying part being apertured and preventing access to the other, in combination with means on one of said parts operative by relative movement of the element to be attached for securing said element to said part, one of said parts being engageable by means insertable through the aperture in the other, whereby relative move- 75

75 100

- ment of said part and said element may be produced.
2. An attaching device comprising a member and a relatively movable socket, said member overlying said socket and preventing access thereto and being apertured, in combination with means in said socket operative by relative movement of the element to be attached for securing said element in said socket, said socket being engageable by a key inserted through the aperture in said member for holding said socket whereby reversed relative movement of said element may release the same.
3. An attaching device comprising an outer part inclosing an inner part relatively movable therein, means on said inner part operative by relative movement of the element to be attached for securing said element to said inner part, said inner part being engageable by means insertable through said outer part whereby relative movement of said part and said element may be produced.
4. An attaching device comprising in combination a shell, a socket in said shell adapted to receive the element to be attached, said socket being movable with said element to prevent removal of said element, said socket being engageable by means insertable through said shell, whereby said element may be moved relative to said socket to disengage said element from said socket.
5. An attaching device comprising an apertured shell and a nut swiveled therein to receive the element to be attached, said nut having a groove engageable by a key insertable through the shell aperture for holding said nut to permit said element to be unscrewed.
6. An attaching device comprising in combination a member having a nut swiveled thereto, in combination with means on said member and means on said nut engageable by a key for locking the swivel.
7. An attaching device comprising in combination a shell having a nut swiveled therein, means carried by said nut for receiving a key for preventing rotation of said nut, said shell having an aperture to admit the key to said means.
8. An attaching device comprising in combination a shell, a nut swiveled in said shell, said shell having a mouth aligned with the bore of said nut, the element to be attached passing through said mouth and engaging said bore, said nut being engageable by means insertable through said shell for holding said nut to permit said member to be disengaged from said bore.
9. In an attaching device, a shell, a member mounted in said shell, said member having an outer surface of revolution and an internally threaded end and a non-circular portion at the opposite end, said shell having at one end a mouth axially aligned with said internally threaded portion, and said shell having an aperture at the opposite end admitting a key to said non-circular portion.
10. A shell having a reduced end forming a mouth and an annular shoulder and a cap closing the other end of said shell, a nut swiveled in said shell between said shoulder and said cap, said nut and cap having registering non-circular apertures to receive a key, said cap and the wall of said shell having registering apertures; and a bail having the ends thereof mounted in said registering apertures of said shell and cap.
11. A pencil attaching device comprising a chained shell having an aperture, relatively movable socket means inclosed in said shell, means on said socket means operative by relative movement of the pencil to be attached for securing said pencil in said socket means, said socket means being engageable by means insertable through the aperture in said chained shell whereby relative movement of said socket means and said element may be produced.
- In testimony whereof I have signed my name to this specification.
